ELECTRIC DISCHARGE TUBE

Johan Lodewijk Hendrik Jonker and Gerard Charles Antoine Marie Moubis, Eindhoven, Netherlands, assignors, by mesne assignments, to Radio Corporation of America, New York, N. Y., a corporation of Delaware.

Application October 5, 1938, Serial No. 233,362
In the Netherlands October 13, 1937

5 Claims. (Cl. 250—162)

This invention relates to a device comprising an electric discharge tube for indicating voltages hereinafter termed "tuning indicator."

Such tuning indicators for use in wireless receiving sets, measuring apparatus or the like are known in various forms one of the kind most in use at the present day being that in which the electron current emerging from a cathode is controlled by an electrode having a positive potential and being preferably shaped in the form of a rod, the electron-current striking a fluorescent anode. This electrode system may be assembled in a single tube with a second electrode system surrounding the same cathode, the control electrode of the first-mentioned system being connected to the anode of the last-mentioned one.

The present invention relates to a device comprising a tuning indicator of a construction which is widely different from that hereinbefore mentioned; according to the invention the electrons emanating from the cathode of the tuning indicator are accelerated by an accelerating anode and then united by an electronic lens to form a diverging beam. A portion of this beam is then cut out by a diaphragm at some distance in front of the fluorescent screen and the beam which passes through the aperture of the diaphragm forms on the fluorescent screen an image of a given shape which is substantially identical with that of the aperture in the diaphragm.

In contradistinction to the well-known indicators a tuning indicator of the said kind is very similar to cathode-ray tubes, but the great difference from the well-known cathode-ray tubes is that the screen has projected on it a diverging beam from which a part is cut out by a diaphragm. The well-known tubes, such as Braun tubes or the like, are so constructed that either a converging beam or a parallel beam from which a portion is cut out by an aperture formed in one of the electrodes is thrown on to the screen.

In a tube in a device according to the invention the focal distance of the electron-diverging lens may be altered by modifying the potential of at least one of the electrodes that constitute the lens. Thus the distance of the focus of the lens from the diaphragm is also altered and the part which is cut out from the beam by the diaphragm will be possessed of a different divergence and consequently form on the fluorescent screen a larger or smaller image. It has been found that in spite of the focal distance being altered the image on the screen conserves its definition.

55 In one form of construction of the present in-

vention, the voltage to be indicated by the indicator is placed with advantage on one of the electrodes of the lens, the best result being obtained if a negative bias is applied to this electrode and if use is made of such a device that the voltage to be indicated reduces the negative bias of the said electrode and thus increases the divergence of the part of the beam which is cut out by the aperture in the diaphragm and the image of this aperture on the fluorescent screen. By placing a negative bias on the electrode to which the voltage is applied it is ensured that when in rest the beam yields but a very small spot on the fluorescent screen.

The diaphragm may be internally connected to the electrodes arranged in front and at the back of it so that these three electrodes are at the same voltage; the diaphragm may have an extension, for example cylindrical, which surrounds the electron path at least partially.

The electronic lens is preferably formed between two or more electrodes which have, for example, a circular aperture and which are given such voltages that they exercise a diverging influence on the beam of electrons. In one embodiment of the invention the accelerating anode may form part of the electronic lens.

In order that the invention may be clearly understood and readily carried into effect it will now be described more fully with reference to the accompanying drawing, in which a device according to the present invention is shown.

Referring to the single figure of the drawing, 1 designates a tuning indicator having a cathode 2, an accelerating anode 3, two electrodes 4 and 5 in each of which an aperture is formed, a diaphragm 6 in which the aperture to be reproduced is formed and an electrode 7. Intermediate the electrodes 4 and 5 an electronic lens is formed by connecting one of these electrodes to a tapping of a potentiometer 8 arranged between the positive terminal of a source of high voltage and the earth. Said potentiometer is possessed in addition of tappings for the electrodes 2, 3, 6 and 7. The electrode 6 has formed in it a star-shaped aperture and the divergent beam formed by the electrodes 4 and 5 passes for a small part through this aperture and then falls on to a fluorescent screen 9 arranged at the end of the tube thereby forming an enlarged replica of the aperture on the fluorescent screen. The electrode 4 of the lens is connected to the point whose voltage is to be reproduced optically. In the circuit shown this is a point of a wireless receiving circuit in which the tube 1 indicates the tuning of a

set. The circuit comprises a diode which detects the high-frequency alternating voltage and thus sets up a potential difference across the resistances 11 and 12. The point A is thus given a positive voltage which is supplied to the electrode 4 through an electric filter formed by a resistance 15 and condensers 13 and 14. The said electrode 4 is given a negative bias relatively to the cathode 2 since the latter is connected to a tapping of the potentiometer 8. The negative bias of this electrode 4 is established so that the image on the fluorescent screen has minimum dimensions. If the negative voltage of the electrode 4 is decreased due to the fact that the point 15 A is given a positive voltage, the dimensions of the fluorescent image are increased. The point A is most positive when the set is tuned completely and the correct tuning is therefore found by adjusting to the maximum size of the image on 20 the fluorescent screen. As an alternative, the electrode 4 may be given a positive bias and in this case the negative voltage is tapped off, for example, the point B. Thus the size of the fluorescent image decreases on the set approaching 25 its tuning. In the circuit shown the resistances 11 and 12 form a potentiometer the point C of which is earthed.

Obviously, the electrode 4 may have supplied to it any voltage to be measured and the invention 30 is not limited to the use of tuning indicators in wireless receiving sets.

What we claim is:

1. An electronic tuning indicator tube having an electrode structure consisting of an electron 35 source to generate an electron beam, an electron responsive target oppositely disposed from said electron source, a pair of electrically connected apertured electrodes with their apertures axially aligned between said electron source and said 40 target and the electrode of said pair nearer the said target being the electrode most adjacent said target, an intermediate apertured electrode between said pair of electrodes, electrode means between said two electrodes and said electron 45 source to control the divergence of the electron beam through the aperture of said intermediate electrode to electronically image the aperture in said intermediate electrode over continually diverging paths on said target.

50 2. An electronic tuning indicator tube comprising an evacuated envelope enclosing a source of electrons and electrode structure consisting of an oppositely disposed target adapted to become luminescent when bombarded with electrons from 55 said source, means comprising an apertured anode to maintain the emission from said source substantially constant, three axially aligned apertured electrodes between said anode and said target, the aperture of the intermediate electrode 60 of said three electrodes being non-circular and one of said three electrodes being wholly exposed to said target and being the nearest to said target

of any electrode in said envelope, and electrode means between said anode and said three electrodes to electronically image the noncircular aperture on said target over an area on said target which is greater than the area of said noncircular aperture. 5

3. An electronic indicator tube having an evacuated envelope enclosing a fluorescent screen, a cathode oppositely disposed from said screen, a pair of electrically connected apertured electrodes 10 between said cathode and said screen, one of said pair of electrodes being closer said screen than any other electrode in said tube, an electrode having a noncircular aperture, said electrode being positioned between said pair of electrodes, and 15 electrode means between said cathode and said pair of apertured electrodes to direct electrons from said cathode to said screen over paths diverging from a direct line between said cathode and said screen over the entire distance between 20 said electrode having the aperture and said fluorescent screen.

4. An electronic tuning indicator tube having an evacuated envelope, a fluorescent screen within 25 said envelope, and electrode structure within said envelope comprising a cathode oppositely disposed from said screen, a system of three apertured electrodes between said cathode and said screen, the electrode of said system nearest said screen being the closest electrode to said screen 30 of all the electrodes within said envelope to cause electrons emitted from said cathode to follow paths toward said screen which continuously diverge over the distance separating said system of electrodes from said screen, and means including 35 an apertured electrode between said three electrodes and said cathode to maintain the diameter of the beam impinging on the intermediate electrode of said system of three electrodes greater than the aperture in said intermediate electrode 40 to image said aperture on said screen.

5. An electronic indicator tube having an envelope enclosing an electron source to emit a beam of electrons, an anode adjacent said source to accelerate the beam of electrons, a fluorescent 45 screen oppositely disposed from said source to receive electrons from said source, a noncircular electrode having an aperture axially aligned with said cathode and anode between said anode and said screen, the noncircular electrode on each side 50 of said electrode having an aperture, and electrode means between said electron source and the next adjacent electrode in the direction from said source to said screen to direct upon said screen a beam of electrons having a constantly 55 increasing diameter throughout the space from said electrode having the aperture to said screen to image an enlarged replica of said noncircular aperture on said anode. 60
